STOP MOTION FOR TEXTILE MACHINES

Mitchell M. Rosenstein, Willimantic, Conn.

Application February 12, 1948, Serial No. 7,732

11 Claims. (Cl. 66—166)

1

This invention relates to a stop motion for textile machines and more particularly to such a device for fabric knitting machines.

An object of the invention is to provide a device which will become operative to stop a textile machine upon the occurrence of a fault in the structure of the fabric produced thereby, such as may be caused by a skipped stitch or a failure in the knitting or weaving operation, such as commonly due when one or more threads break in the machine before they reach the fabric which is being produced therefrom.

A further object of the invention is to provide such a device having one or more probes or the like, which are constantly in motion and in contact with the cloth so that a defect occurring therein will be quickly detected by the device and the operation of the machine stopped.

Further objects and advantages of this invention will be more clearly understood from the following description and from the accompanying drawings, in which—

Fig. 1 is a diagrammatic end view of a portion of a knitting machine, having my improved stop motion device applied thereto.

Fig. 2 is a bottom view showing the said stop motion device in operation upon a piece of fabric and the electric circuit for controlling the operation of said device.

Fig. 3 is an enlarged end view of my improved stop motion device.

Fig. 4 is a plan view of a portion thereof.

Fig. 5 is a rear view of said device on the same scale as illustrated in Figs. 1 and 2, showing a driving mechanism therefor.

Fig. 6 is a fragmental view similar to Fig. 4 but showing the device in operative position.

Fig. 7 is a fragmental view illustrating a modified form of probe mechanism.

Fig. 8 is a side view showing the end of a probe for a closely knit cloth.

Fig. 9 is a similar view showing the tip of a probe for a loosely knit or wide mesh cloth.

As shown in the drawings, the numeral 5 denotes a spool from which a plurality of threads 6 are supplied to a bank of needles, indicated at 7, which knit the said threads into a fabric 8. This fabric may be knitted in different widths and it is usually wound on a fabric roll 9.

Further description of the knitting machine illustrated is herein omitted since such machines are commonly known to those skilled in the art and my invention may be applied thereto independently of any variation that may be en-

2

countered in the construction of different types of knitting machines.

Stop motions have been heretofore commonly used on textile weaving and knitting machines. The types most commonly used, however, have consisted of a separate wire member for each thread woven as a warp thread or knitted into the fabric. Such devices are extremely complicated and require a great deal of time in the setting up and maintenance of the machines. Such devices have also been found impractical for use on knitting machines and, consequently, it has been necessary to depend on the skill and alertness of the operator in detecting a flaw in the fabric or a failure in the knitting operation such as commonly caused by a broken thread or other irregularities in the condition and operation of the machine. The most common failures have been found to be due to the breaking of threads, indicated at 6, before they are knitted into the fabric. Such breakage causes a rip or slit in the finished fabric and, unless the operator of the machine is alert and quick to detect this fault and stop the machine, a considerable amount of cloth may be produced with flaws therein and thereby cause costly waste of material since such defective fabric must be discounted since it is practically useless.

My invention is therefore particularly directed to the provision of a simple and efficient device which will constantly inspect the fabric and immediately stop the machine upon detecting a flaw therein.

This invention may be embodied in the device such as illustrated herein wherein the numeral 10 denotes a supporting bar which may extend across the machine or for any desired distance. A track 11 is carried upon the said bar. This track is preferably in the form of a plate having the edge proportions thereof extending beyond the sides of the supporting bar.

A desired number of carrier members 12 are mounted upon said track and each of said members is provided with depending flanges 13 which extend under the edge portions of the track 11 and slidably retain the said carrier member 12 thereon.

A contact plate 14, having contact points 15—15, is carried upon the carrier member 12. This contact plate is preferably pivoted to the carrier member by means of a stud 16 and nut 16a.

The said contact plate 14 is normally retained in inoperative position by means of springs 17—17 which are anchored to the carrier mem-

ber 12 and secured to the said contact plate so as to normally retain it in alignment with the carrier member 12.

A probe, preferably in the form of a bar 18, is carried on a rocker member 19 which is pivotally mounted in posts 20 that are carried on the contact plate 14. A spring 21 is carried on said contact plate and secured to a lever 22, projecting from the said rocker bar, for normally urging the probe 11 into contact with the fabric 8. The end of said probe is provided with a tip 23 which engages the under side of the cloth as it is knitted in the machine. This tip projects above a shoulder 24 that is provided for the purpose hereinafter described.

Different forms of tips may be provided, in the ends of the probes 18, in accordance with the particular mesh or grade of the fabric. When a closely knit fabric is to be produced, a narrow tip, such as 23, is used. When a coarse or wide mesh fabric is produced, a large tip 25, such as shown in Fig. 9, may be used. This tip may also have an adjacent shoulder which is preferably provided as indicated at 26.

In order to move the carrier member 12 upon the track 11, I provide a drive belt 27 which is preferably mounted on the sheaves 28-28 at the opposite ends of the bar 10. This belt may be in the form of a cable or other flexible means, such as a chain or the like.

As illustrated in Fig. 5, a mechanism is provided for reciprocally moving the said belt. This device may consist of a lever 29 which is pivotally mounted as at 30, to a suitable support, such as the floor indicated at 31, and may be driven by a motor 32 through a suitable speed reducing device 33 and a crank rod 34 which may be secured to the lever 29 for operating the same. The said lever is connected to the belt 27 by means of a pitman 35 and a suitable clamp 36 for operating the said belt as will be hereinafter described.

It will be noted that the belt is secured to each of the carrier members 12 by clamping means, preferably in the form of a projection 37 from said member, carrying a suitable clamping member 38 thereon which engages the belt and secures it to the carrier member.

If desired, means may be provided for moving and holding the probes out of contact with the fabric whenever it may be found necessary, such as at times when the machine is being rethreaded for different types or sizes of fabric, or when a break should occur in one or more threads and it becomes necessary to readjust the machine and access to the needles 7 or other parts of the machine is required.

Such means may comprise a cross bar 39 which extends along the supporting bar 10, over the probes 18 carried thereon and out of contact with said probes. This bar is mounted on levers 40-40 which are carried on and rotate with an operating bar 41 that is pivotally mounted on brackets 42-42. A handle 43 may be provided for rocking the said operating bar 41.

In order to control the operation of the machine by means of my improved stop motion device, I provide an electric circuit, such as illustrated in Fig. 2, wherein there is included a contact bar 44 which is mounted on the supporting bar 10 and insulated therefrom and from the contact plates 14, by means of the insulating posts 45.

The said electric circuit also includes therein a motor 46, which drives the entire knitting ma-

chine, and the motor 32 which operates the stop motion mechanism. While the said motors are shown as separate, one motor may be used for driving both the machine and the stop motion mechanism, since the cable 28 may be operated directly by a part of the machine instead of by the separate motor and mechanism illustrated in Fig. 5. The said circuit further comprises a pair of conductors 47-48 which are connected to an electric supply and to the primary side of a suitable transformer 49. These conductors are also connected to the motors 32 and 46, by means of conductors 50-51, through a main switch 52, and a relay switch 53, the said motors being connected in said circuit in parallel.

A conductor 54 is grounded to the supporting bar 10 and connected to the secondary side of the transformer 49, and a conductor 55 is connected from the opposite end of said secondary side of the transformer through a relay solenoid 56 and a conductor 57, to the contact bar 44.

It will be understood that when it is desired to set the knitting machine in operation, it is simply necessary to close the main switch 52. This will energize the electric circuit and the motors 32 and 46 which are included therein. The motor 46 will then drive the machine while the motor 32 will operate the stop motion device.

The operation of my improved stop motion device is as follows:

After the machine is set in motion and the motor 32 becomes energized, the lever 29, through the pitman 32, applies a reciprocating movement to the belt 27. This movement may be adjusted for predetermined distances and depends upon the connection between the crank lever 34 and the lever 29. This reciprocating movement of the belt is transferred to the carrier members 12 which carry the probes 18, and said probes are thereby moved with a reciprocating movement crosswise to the direction of travel of the fabric and in contact with the bottom thereof.

As long as the cloth is being properly formed, the probes will merely slide in contact therewith and the stop motion device will remain inoperative. When a flaw occurs in the cloth, either through the breaking of a thread or for some other reason, the tip of the probe coming into contact with the flaw will enter the said flaw up to the shoulder 24 or 26 while the movement of the carrier 12 continues. As the tip enters the flaw, the probe 18 will turn the contact plate 14 upon the post 15 against the tension of the springs 17-17, as clearly illustrated in Fig. 6, and thereby bring one of the contact points 15 into contact with the contact bar 44. This will close the electric circuit through the solenoid 56 and cause opening of the relay switch 53 and thereby break the circuit to the electric motors 32 and 46 and stop the operation of the machine as well as the operation of the stop motion device. Upon such stoppage of the machine, the remainder of the electric circuit, which extends through the stop motion device, may be broken by opening the main switch 52 while the machine is being reconditioned.

As illustrated in Fig. 2, it will be noted that a plurality of probe units may be used adjacent to each other and movable in common upon the track 11. These units may be spaced apart for any desired distance in order to accommodate fabrics of different widths. For instance, in the fabric such as illustrated in Fig. 2, it may be desired to use three separate probes, each one traveling for a predetermined distance, which

will overlap the travel of the adjacent probe so that a closer inspection of the cloth may be provided by permitting faster reciprocating movement of the probes in proportion to the speed with which the fabric is produced and moved past the probes.

When my device is used on a narrow strip of fabric, one probe may be sufficient, while for a wider fabric, more probes may be used and their speed and distance of travel may be regulated by adjustment of the driving mechanism so as to provide the desired coverage over the surface of the fabric for the closeness of inspection required.

In cases where the fabric is produced with a combination of different textiles, such as a close knit and a loose knit, the appropriate probe tips may be used in the ends of the probes and the distance traveled by the probes may be adjusted in proportion to the width of the particular strips in the fabric.

When it is desired to move all of the probes away from the fabric to permit access to parts of the machine, the handle 43 may be used to merely rock the bar 41 and thereby, through the levers 40-40, swing the cross bar downwardly upon the tops of all the probes and move them against the tension of the springs 21, to the position indicated in dotted lines in Fig. 3.

In the form illustrated in Fig. 7, the probes 18 may be detachably secured to a socket 59 which is carried on the rocker bar 19.

If desired, the said rocker bar may be provided with a detent 59 which will engage the end of a pawl 60 having a button 61 at the opposite end thereof. This arrangement will permit the probes to be individually retained in a position away from the fabric. By merely pressing the probe downwardly, the pawl 60 will move into contact with the detent 59 and hold the probe down against the tension of the spring 21. When it is desired to release the said individual probe, the button 61 may be pushed down to thereby disengage the detent and permit the spring 21 to return the probe to its normal operative position.

I claim:

1. A stop motion device for knitting machines and the like comprising a supporting member extending substantially across the machine, a carrier slidably movable upon said support in a direction transverse to the direction of travel of the fabric produced in the machine, a probe mounted on said carrier and extending therefrom into contact with the fabric, an electric circuit, a motor in said circuit for operating the machine, and means rendered operable by the movement of said carrier upon the engagement of said probe with a flaw in the fabric to cause opening of said circuit and stoppage of the machine.

2. For a knitting machine and the like, a stop motion device comprising a support running transversely to the machine, a carrier reciprocatingly movable on said support, a contact member movably carried on the carrier, a probe extending from said contact member and having a tip in contact with the fabric, whereby the said tip is provided with a probing movement running transversely of the direction of travel of the fabric in the machine, an electric circuit, means rendered operable by the movement of said contact member upon engagement of the said tip with a flaw in the fabric to effect said electric circuit, and means controlled by said electric circuit for stopping the operation of the machine.

3. For a fabric knitting machine and the like,

a stop motion device comprising a support running transversely to said machine, a track on said support, a carrier reciprocatingly movable on said track, a contact plate swivelly connected to said carrier, means for normally retaining said contact member in alignment with said carrier, a probe extending from said contact member and having a tip in the end thereof engaging the surface of a fabric being produced in said machine, a contact bar running along said track and insulated from the said contact member, an electric circuit connected to said contact member and bar, means rendered operable by the movement of said carrier upon the engagement of the probe tip with a flaw in the fabric to cause contact between the contact member and the contact bar to thereby close said circuit, and means rendered operable upon closing the said circuit for stopping said machine.

4. For a knitting machine and the like, a stop motion device comprising a support running transversely of the machine, a track on said support, a carrier slidably mounted on said track, means for applying reciprocating movement to said carrier, a contact member on said carrier and movable relatively thereto, a probe extending from said carrier into contact with the surface of a fabric being produced in the machine while in motion with said carrier, a contact bar insulated from said contact member, an electric circuit, and means for normally retaining said contact member out of engagement with said contact bar, the said contact member being movable into contact with the contact bar upon engagement of the probe with a flaw in the fabric to control the said electric circuit, and means operable upon closing of said electric circuit for causing stoppage of the machine.

5. For a knitting machine and the like, a stop motion device comprising an elongated support extending substantially crosswise to the machine and to the direction of travel of the fabric produced in said machine, a carrier slidable on said support, means for reciprocatingly moving said carrier along said support, a probe carried by the carrier and extending therefrom into contact with the surface of the fabric, an electric circuit, means rendered operable by movement of said carrier, upon the engagement of the probe with a flaw in the fabric, to effect said circuit, and means controlled by said circuit for causing stoppage of the machine.

6. For a knitting machine and the like, a stop motion device comprising an elongated support extending substantially transversely to the machine and to the direction of travel of the fabric produced thereby, a carrier movably mounted on said support, means for reciprocatingly moving said carrier upon the support, a contact plate swivelly secured to the carrier, a probe pivotally mounted on said contact plate, means for resiliently retaining said probe in contact with the surface of the fabric, a contact bar insulated from said plate, an electric circuit connected to said plate and bar, means for normally retaining the contact plate out of contact with the bar, the said contact plate being caused to rotate upon the carrier and contact said bar, upon engagement of the probe with a flaw in the fabric, to thereby close said circuit, and means rendered operable upon closing of the circuit to cause stoppage of the machine.

7. For a knitting machine and the like, a stop motion device comprising an elongated support extending transversely to the machine and to the direction of travel of the fabric produced

therein, a plurality of spaced carriers on said support, each of said carriers having a probe extending therefrom into contact with the surface of the fabric, means for simultaneously and reciprocatingly moving said carriers upon the support, whereby the probes are moved crosswise to the fabric while in contact therewith to thereby probe the fabric for the entire width thereof, and means operable, upon engagement of any one of said probes with a flaw in the fabric, to cause stoppage of the machine.

8. For a knitting machine and the like, a stop motion device comprising an elongated support extending transversely of the machine, a plurality of carriers slidably mounted on said support, means for reciprocatingly moving said carriers, a probe extending from each of the carriers into contact with the surface of the fabric and movable by the carrier in a direction transversely to the direction of travel of the fabric, means operable, upon engagement of at least one of said probes with a flaw in the fabric, to cause stoppage of the machine, and means for simultaneously moving all of said probes away from said fabric.

9. For a knitting machine and the like, a stop motion device comprising a support, a plurality of carriers movable on said support and adjustable for different distances there between, common means for simultaneously and reciprocatingly moving said carriers on the support, each of said carriers having a contact member carried thereby and movable thereon, a probe extending from each of said contact members into contact with the surface of said fabric, means for resiliently retaining said probe into contact with the surface of the fabric, a contact bar insulated from said contact members and running along said support, an electric circuit connected to said contact bar and plate, said contact plate being operable by movement of the carrier upon the engagement of the probe with a flaw in the fabric to contact the contact bar and thereby close the said circuit, means operable upon the closing of the circuit to stop the machine, and means for individually retaining said probes out of engagement with the fabric.

10. For a knitting machine and the like, a stop motion device including a probe, mechanism for

retaining said probe in engagement with the surface of a fabric produced in said machine and moving said probe transversely to the direction of travel of said fabric, the end of said probe containing a tip adapted to enter a flaw in the fabric, a shoulder adjacent to said tip for limiting the movement of the probe after the entry of the tip, and means whereby continuing movement of the carrier after engagement of the tip with the flaw will cause stoppage of the machine.

11. For a knitting machine and the like, a stop motion device including a track member running transversely of the machine and of the direction of travel of a fabric produced in said machine, a carrier reciprocatingly movable on said track, an endless belt movable along said track and engaged with said carrier for applying reciprocating movement thereto, an electric circuit, circuit closing means including a contact member on said carrier and a contact bar running along said track and insulated from the carrier, a probe extending from the carrier into contact with the fabric, a motor for driving said machine and a separate motor for driving said endless belt, the said motors being included in said circuit and said contact plate member being movable, by continuing movement of the carrier upon engagement of the probe with a flaw in the fabric, to control said circuit and cause de-energization of said motors; whereupon the operation of the machine and stop motion device is terminated.
